JOSEPH HERSKOWITZ, OF WOODHAVEN, NEW YORK, ASSIGNOR TO ADOLF HERSKOWITZ & SON, INC., OF BROOKLYN, NEW YORK

OVERALLS

Application filed June 21, 1929. Serial No. 372,678.

This invention relates to wearing apparel and more particularly to drop seat outer garments such as overalls and working clothes designed for mechanics and artisans.

5 One of the objects of my invention is to provide a drop seat outer garment in which the seat proper may be completely opened by a single operation and preferably by means of what is commonly known in the 10 art as a hookless fastener.

More specifically my invention relates to a garment having a semi-circular drop seat extending completely across the rear of the garment so as to provide a maximum opening and including a continuous hookless fastener whereby said seat may be open by a single rotary movement.

I am aware that outer garments of the 20 above type have been made with drop seats equipped with hookless fasteners extending across the back of the garment from side to side in a straight line. It has been necessary however, to split or open the sides of the garment for at least a short distance to permit the seat to be fully opened. The open sides require an additional fastening means such as a button and button hole to completely close the seat. This is an objectionable feature of such a garment for the reason 30 that it necessitates at least three operations, viz. the manipulation of the hookless fastener and the closing of both sides. Furthermore, the sides do not completely close so that in the case of motor mechanics for instance, oil, grease and dirt creep through the side openings defeating the purpose and object of the garment. In addition, the side openings are easily ripped, the buttons are torn away and busy mechanics and workmen 40 cannot take the time to properly close the seat and openings for proper protection.

To overcome the above objections and others which will be readily understood by 45 those skilled in the art and to enable others to fully comprehend the underlying features and improvement in my new outer garment, reference is had to the accompanying drawing showing a preferred form of the invention, in which

Fig. 1 is a front view showing the garment.

Fig. 2 is a rear view showing the drop seat partially opened.

Referring now to the drawings, 5 designates the front, upper body portion of an outer garment such as an overall, and preferably in one piece with the legs 6, 7. Numeral 8 designates the waist band, 9 the top pockets and 10 the side pockets.

Referring particularly to Fig. 2 of the drawing, I have shown the rear body portion 11 of the garment as provided with a semi-circular drop seat or flap designated in its entirety by numeral 12, said drop seat extending from the side 13 to the side 14 and completely across the said garment. The lower edge 15 of the rear body 11 is equipped with the hookless fastener strip which cooperates with a strip 16 on the top edge of the drop seat, said strips being adapted to be opened and closed by the fastener 17 in the manner well known and understood.

It will be thus seen that the drop seat may be completely opened by a single operation and by a single, circular sweep when the fastener 17 is seized by the fingers and the seat closed in the same manner. Since the width of the seat is of the same width as the garment, there are no side openings or additional fastening means employed other than the hookless fastener. The seat provides the maximum opening and completely closes the back of the garment when closed so that no dirt or foreign matter may enter to soil the garments to be protected.

Having shown and described my invention, what I claim as new and desire to secure by Letters Patent is:

A garment of the class described comprising an upper body portion, bottom leg portions, a semi-circular drop seat and a slide fastener for closing said drop seat extending from side to side, the peak of the drop seat being on a line with the waist line of the garment.

In testimony whereof he has affixed his signature.
